(57) **CLAIM**

The ornamental design for an automobile body and/or replica, as shown and described.

DESCRIPTION

FIG. 1 is a top, front and left side perspective view of an automobile body and/or replica showing our new design; FIG. 2 is a rear elevation view thereof;

FIG. 3 is a front elevation view thereof;

FIG. 4 is a top plan view thereof;

FIG. 5 is a left side elevation view thereof;

FIG. 6 is a right side elevation view thereof; and,

FIG. 7 is a top, rear and left side perspective view thereof. The portions of the automobile body shown in broken lines are for illustrative and environmental purposes that form no part of the claimed design.

The dot-dash lines depict unclaimed boundaries between claimed portions, depicted exterior to the dot-dash lines, and unclaimed portions, depicted within the dot-dash lines, of the claimed design.
